UNITED STATES PATENT OFFICE

HENRY MOECKER, JR., OF FLOSSMOOR, AND THEODORE THOMPSON, OF HARVEY, ILLINOIS, ASSIGNORS TO AMERICAN STOVE COMPANY, OF ST. LOUIS, MISSOURI, A CORPORATION OF NEW JERSEY

GAS RANGE

Application filed December 3, 1928. Serial No. 323,460.

This invention relates to improvements in gas ranges and is more particularly directed to a sheet metal assembly or construction of high shelf brackets and splasher backs therefor.

5 The primary object of the invention is the provision of a sheet metal assembly of a high shelf bracket and splasher back construction for ranges.

10 Another object of the invention is the provision of a sheet metal assembly of the character described and so assembled and finished as to present a smooth, symmetrical design which is pleasing to the eye and which can be assembled to the range quickly and economically with the use of a minimum number of bolts.

15 A still further object of the invention is the provision of an assembly of the type described which from the standpoint of manufacture is a finished article complete for use on a gas range without the necessity of attaching any trim or ornamentation.

20 A still further object is the provision of an assembly of the character described which effects a considerable saving in that it is made of sheet metal rather than of the conventional cast-iron and is as a consequence provided with a porcelain enameled finish at a cheaper 25 cost.

25 Another and further object of the invention is the provision of an improvement in assemblies of the character described which by reason of its being cut from a large sheet 30 of metal on a punch press makes possible extremely low cost in production.

35 Other novel features of construction, improved results and objects of the invention will appear from the following specific 40 description taken together with the accompanying drawings.

In the drawings:

Figure 1 is a view in front elevation of a stove embodying the present invention.

45 Figure 2 is a back view of the stove appearing in Figure 1.

Figure 3 is a fragmentary horizontal sectional view through the shelf bracket and a portion of the splasher back.

50 Figure 4 is a perspective view of the shelf.

bracket and splasher back the parts being shown in strung-out or unassembled relation.

Figure 5 is a plan view of a metal sheet cut into proper shape to be formed into a shelf bracket.

Figure 6 is horizontal sectional view illustrating the cross sectional configuration of the bracket.

Referring now to the drawings and particularly to Fig. 1 which illustrates the more or less conventional form of gas range it will be seen that A is the stove frame base supported above the floor by the usual legs, B and having mounted thereupon a broiling oven C and baking oven D at one end while at its other end is the usual cooking top E at the back of which is the splash plate or splasher back F above which is a shelf G supported at one end by the high shelf bracket H.

Before proceeding with a detailed description of the specific invention attention is directed to the fact that the present inventive idea as expressed in the claims forming a part of this specification can be applied to 75 stoves of many different characters without departing from the spirit of the invention as expressed in those claims.

The high shelf bracket has been previously referred to and indicated as an entirety by 80 the letter H. This bracket is in reality made up of two parts, one of which is indicated by the numeral 10 and is in effect the main bracket or what may be termed the outer shell while the second part is indicated by 85 the numeral 11 and we have termed this part the bracket lining.

The bracket shell or part 10 is cut from a sheet of metal on a punch press into the shape indicated in Fig. 5 of the drawings and then 90 bent or formed on a forming press into the shape or configuration appearing in Fig. 4 of the drawings wherein it will be seen there is a main outer wall 12 which at its lower end is narrow and provided with an inwardly 95 bent portion 13 forming a bottom while at its top end this wall is broad and provided with an inwardly bent or extending portion 14 forming a top. At its front edge this wall 12 is provided with an inwardly extending 100

or bent portion 15 forming a front which front in turn has an inwardly bent flange 16 which gives to the front of the shell a finished appearance and which edge forms a specific function which will be hereinafter more specifically pointed out. The bracket at its rear is provided with a back 17 which back has extending throughout its length and at right angles to itself a flange 18.

From the foregoing it will be seen that the bracket part 10 is in reality a shell having one open side and the bracket lining 11 is formed to fit and be retained within this shell as clearly appears in Fig. 3 of the drawings.

The bracket lining has a wall 19 which is similar in configuration to the wall 12 of the bracket shell and has a top portion 20 and a bottom 21. At its front edge the lining is provided with an inwardly curved portion 22 having throughout its length a depression 23. The portion 22 is of a similar configuration to the front 15 of the shell. At its rear edge the portion 19 of the lining is provided with a V-shaped bulge 24 terminating in a straight wall 25 extending the length of the lining which wall in turn terminates in an inwardly bent flange 26 which also extends throughout the length or height 30 of the lining.

The dimensions of the lining are such that it will fit within the shell in the manner indicated in Fig. 3 of the drawings wherein it will be seen that the flange 16 of the shell 35 overlaps the depressed portion 23 of the lining while the front edge 22 of the lining abuts the inner face of the front wall 15 of the shell. This overlapping between the shell and the lining at their front edges locks the lining within the shell at this point.

Referring to the splasher back or plate it will be seen that this member is of a length corresponding to the distance between the inner wall 27 of the oven and the high shell bracket H while it is of a height equal to the height of the bracket. At its top and bottom edges the splasher plate is offset rearwardly to form L-shaped seats 29 and 30 each of which seats is provided with a back 50 or flange 31 and 32 respectively.

This plate at its end adjacent the oven wall 27 is offset to form a seat 33 which is provided with a back or flange 34. At its end adjacent the high shelf bracket the splasher plate is provided with an offset forming a seat 35 and a rearwardly extending flange or wall 36.

By reference to Fig. 4 of the drawings it will be seen that in assembling the high shelf bracket together with the splash plate that the wall 25 at the inner end of the shelf lining engages the seat 35 of the splash plate and that the flange or wall 36 of the splash plate abuts the flange 18 of the bracket shell.

In assembling the parts and fastening them

to the range it will be seen that the inner bracket lining is retained in the shell without the use of any bolts whatsoever. The shell is fastened to the top of the range by suitable bolts which pass through suitable openings 37 in the bottom 13 of the shell which fastening is effected before the inner lining is put into place.

The oven shelf G is supported upon the top 14 of the shell and fastened thereto by suitable bolts which pass through the openings 38 in the shell top 14 while at its opposite end the shelf is bolted to the inner oven wall 27.

The bracket inner lining is now placed in the shell and then the splash back or plate is positioned in the manner indicated in Fig. 3 of the drawings.

By reference to Fig. 2 of the drawings it will be seen that the splash plate is fastened to the cooking top at its lower edge by a suitable bolt 39 and that the offset portion 30 at the lower end of the back rests upon the top of the stove. Throughout the major portion of its length the rear edge of the shelf G rests upon the offset portion or seat 29 at the upper edge of the splash back and the splash back is attached to the shelf by means of a suitable bolt 40. The offset portion or seat 33 abuts the inner oven wall 27 while the flange 34 overlaps the back of the oven and is attached thereto by suitable bolts 41.

The flange 18 of the bracket shell and the flange 36 of the splash plate are securely clamped together by means of bolts 42. This clamping of the shell and the splash back together securely locks the bracket lining in place.

A conventional form of back for the shelf G is provided as indicated at 44 and is bolted in place in any desirable manner such as indicated at 45 in Fig. 2.

From the foregoing it will be understood that the bracket shell is made in one piece of metal and in Fig. 5 which illustrates the blank from which the shell is made the corresponding parts of the shell have been given the corresponding numerical designations.

It will also be readily apparent that this bracket will present a most pleasing appearance because of its smoothness and pleasing symmetrical designs. It will also be obvious that the lining will greatly strengthen the construction.

Time, labor and money are saved in assembling the bracket part because no bolts are used. From the front of the range no bolts whatever can be seen as they are all at the back of the range. The splash back is quickly and easily bolted into position and due to its connection with the stove parts that it abuts it is easily cleaned. The bolts which fasten the bracket shelf to the stove top and to the stove shelf are hidden from view.

As will be readily apparent from an examination of the drawings it will be seen that the front edge of the bracket shell curves or flares outwardly at its ends to give to the front of the bracket shell a pleasing configuration. To further add to the appearance of the bracket the outer or side wall 12 is provided with a panel effect 50.

Having thus described our invention what we claim and desire to secure by Letters Patents is:

1. An assembly for ranges or the like comprising a shelf bracket and a splash back, said bracket composed of two pieces, one of 15 said bracket pieces rigidly attached to the range, and the other of said bracket pieces retained in position through interlocking connection with the fixed bracket piece and the splash back.

2. In combination with a range having a shelf, a bracket for said shelf and a splash back for the range, said bracket composed of a shell open at its inner side and a lining closing said open side, said lining telescoping 25 the shell, and the splash back rigidly attached to the shell and abutting the bracket lining, thereby holding the lining against displacement.

3. An assembly for ranges or the like comprising a shelf bracket and a splash back, 30 said bracket composed of a shell and a lining, said lining being retained in said shell by telescoping the shell at its front edge and having interlocking engagement at its rear edge with the splash back.

4. In a gas range or the like, a shelf bracket composed of a shell having one open side, a lining closing said open side and telescoping the shell at its front, a splash back 40 at the rear of the range and connected to the rear of the bracket shell, and said splash back abutting the rear end of the shell lining and holding it in locked position.

5. An assembly for use with a range having a splash back comprising a shell and a lining placed together to form a hollow bracket, said lining retained in position 45 through telescopic engagement with the shell and interlocking engagement with the splash back.

6. In a gas range or the like a shelf bracket composed of a shell having one open side, a lining closing said open side and telescoping all the walls of the shell with the exception 55 of its rear wall, a splash back at the rear of the range, one end of said splash back rigidly attached to the bracket shell and having abutting and interlocking connection with the rear end of the lining, thereby locking the lining against displacement.

7. In a gas range or the like having a shelf, a bracket for said shelf composed of a shell having one open side, the bottom of said shell rigidly attached to the stove top and 65 the top of said shell attached to and sup-

porting the shelf, a lining telescoping and closing the open side of the shell, a splash back rigidly attached to the stove and to the bracket shell, said splash back abutting and having interlocking connection with the shell lining, thereby locking the lining against displacement from the shell.

8. In a gas range or the like having a shelf, a bracket for said shelf composed of a shell having one open side, the bottom of said shell attached to the range top and the top of said shell supporting the shelf, a rearwardly extending flange at the back of said shelf, a lining telescoping and interlocking with said shell and closing its open side, said lining adjacent 70 its rear edge provided with an approximately V-shaped bulge, the rear edge of said lining L-shaped in respect to said bulged portion, a splash back provided with a flange abutting and rigidly connected to the flange at the rear of the bracket shell, and said splash back provided with an offset engaging and interlocking with the rear wall of the bulged portion of the lining and the L-shaped end beyond the same, whereby the lining is locked 75 against displacement from the shell and the front wall of the bulged portion of the lining forms an oblique joint with the splash back.

9. A two piece bracket each piece being stamped out and formed from a sheet of metal, one of said pieces being a shell and the other a lining therefor, and the pieces together forming a hollow bracket.

10. A two piece bracket each piece being stamped out and formed from a sheet of metal, one of said pieces being a shell having an open side and the other a lining having an open side, said lining telescoping the shell and closing the open side thereof, the open sides of the pieces being positioned face to face and together forming a hollow bracket.

11. A two piece bracket each piece being stamped out and formed from a sheet of metal, one of said pieces being a shell having a narrow lower end and a wide upper end and an open side, the other piece being a lining telescoping said shell and closing the open side thereof, and the two pieces together forming a hollow sheet metal bracket.

12. A two piece bracket each piece being stamped out and formed from a sheet of metal, one of said pieces being a shell having a narrow lower end and a wide upper end and an open side, the front of said shell curving outwardly at its ends, the other piece being a lining telescoping said shell and closing the open side thereof, and the two pieces together forming a hollow sheet metal bracket.

13. In a gas range or the like, a shelf bracket composed of a shell having one open side, a lining telescoping the shell and closing its open side, the front edge of said shell provided with a flange, and the front edge of the lining provided with a depression, the flange 130

of the shell front engaging the depression in the front edge of the lining, a splash back at the rear of the range and connected to the rear of the bracket shell, and the said splash back abutting the rear end of the shell lining and holding it against displacement from the shell.

14. An assembly for ranges or the like comprising a shelf bracket and a splash back, said bracket composed of a shell and a lining, said lining being retained in said shell by telescoping the shell at its front edge and having abutment at its rear edge with the splash back.

15. An assembly for use with a range having a splash back, said assembly comprising a shell and lining placed together to form a hollow bracket, said lining retained in position through telescopic engagement with the shell and abutment with the splash back.

16. In a gas range or the like having a shelf, a bracket for said shelf composed of a shell having one open side, the bottom of said shell rigidly attached to the stove top and the top of said shell attached to and supporting the shelf, a lining telescoping and closing the open side of the shell, a splash back rigidly attached to the stove, and said splash back abutting the shell lining and locking the lining against displacement from the shell.

In testimony whereof, we hereunto affix our signatures.
